BOTTLE CLOSURE

Merrill M. Kistner, Chicago, Ill., assignor to C. Paul Parker, Evanston, and Chester D. Kern, Chicago, Ill., jointly

Application May 22, 1935, Serial No. 22,754
Renewed January 12, 1940

12 Claims. (Cl. 215—82)

This invention relates to bottle closures and more particularly concerns such closures embodying an improved pouring spout and tamper-proof sealing arrangement.

5 An object of the invention is to provide a bottle closure embodying a compact, unitary assembly adapted to be permanently secured to a bottle or like container and having an improved capped pouring spout over which is secured a 10 novel visible sealing means which must be removed or destroyed upon removal of the cap to discharge liquid from the bottle, thus providing an unmistakable indication as to whether or not the bottle has been opened.

15 Another object is to provide a bottle closure including a capped pouring spout and means for securing the closure to the neck of a bottle or like container which serves to anchor a ribbon-like strip passing over the cap in such a manner as 20 to serve as a tamper-proof seal which must be visibly affected in order to open the closure.

Another object is to provide a bottle closure 25 having a pouring spout closed by a screw cap with a sealing strip overlying the top and opposite sides of the cap and anchored at its ends in such a manner that the cap may be tightened freely without affecting the strip, but when the cap is turned to unscrew the same, the strip will be placed under such tension as either to break 30 it or withdraw its ends from their anchored position, this strip being relatively narrow in the portions adjacent the sides of the cap so as to allow adequate purchase for the finger of a person's hand in turning the cap.

35 Another object is to provide an improved pouring spout of this character which will allow a relatively free entry of air into the bottle when pouring liquid therefrom, and which is fashioned to issue a smoothly and uniformly flowing molded stream of liquid.

Another object resides in the provision of a sealed bottle closure including an improved pouring spout and tamper-proof sealing arrangement 45 embodying a few snugly interfitting metal parts fashioned for simplicity and ease of assembly and forming a complete self-contained unit that may be manufactured cheaply and which is adapted for permanent union with a filled bottle 50 by a simple operation.

Other objects and advantages will become apparent from the following description taken in connection with the accompanying drawings, in which:

55 Figure 1 is a perspective view of a bottle closure

embodimenting the principles of the invention and shown as applied to a bottle.

Fig. 2 is a sectional elevation of the closure and the bottle neck.

Fig. 3 is an exploded view of the bottle closure. 5

Fig. 4 is an elevational view illustrating one manner in which the sealing strip may be removed when opening the closure.

Figs. 5 and 6 are sectional views illustrating 10 various pouring positions of a bottle to which the improved closure is applied.

Fig. 7 is a plan view of a modified form of sealing strip.

Fig. 8 is a perspective view of the device 15 incorporating the modified sealing strip and showing the same as it appears after the seal has been broken.

While the invention is susceptible of various modifications and alternative constructions, I have shown in the drawings and will herein describe in detail the preferred embodiment, but it is to be understood that I do not thereby intend to limit the invention to the specific form disclosed, but intend to cover all modifications and alternative constructions falling within the 25 spirit and scope of the invention as expressed in the appended claims.

The features of the present invention are embodied in a simple, unitary structure fashioned to be assembled as a self-contained commercial 30 unit and which may be affixed permanently to the neck of a bottle or similar container after the latter has been filled with liquid. All parts of the device may be manufactured according to standardized patterns and are cooperatively arranged in such manner that the least possible 35 number of parts is necessary for a complete unit. The unitary closure organization is provided with a tamper-proof seal that must be removed or broken in order to effect a full discharge of 40 liquid from the bottle. Furthermore, the device is adapted to control the volume of discharge of liquid from a bottle having a relatively large neck and to this end provides an improved pouring spout characterized by an arrangement 45 whereby the liquid will flow therefrom in a smooth and uniform, molded stream of the desired volume.

With reference to the drawings, the invention is embodied in a practical form in a closure unit 50 10 which is adapted to be affixed permanently to an annular neck 12 of simple design and forming part of a glass bottle 13 of any desired shape.

In the illustrative embodiment of the invention, the closure 10 includes as a principal element, a 55

thin sheet metal pouring spout 14 which is preferably arranged in such manner that the quantity of liquid discharged from the bottle may be controlled easily and accurately. This is effected by an improved construction whereby air is freely admitted into the bottle to displace discharging liquid, and the flow of liquid is guided in a smooth converging path to issue in a stream sharply defined as to size and volume. To this end, the pouring spout is of a substantially frusto-conical shape with its base of about the same diameter as the interior diameter of the neck 12. A lateral flange 15 is adapted to overlie the end of the neck 12 in parallel relation thereto and defines the position of the spout relative to the bottle neck. The outer and narrower end of the pouring spout is provided with a discharge opening, herein shown as developed into a pouring neck 17 of substantially less diameter than the body of the spout and joined thereto by a gently arcuate shoulder 18. In this manner the effective flow area of the discharge opening provided by the bottle neck is substantially restricted within defined limits. For closing the spout against the escape of liquid, the pouring neck 17 is fashioned to receive suitable capping means being herein provided with threads 19 for receiving a screw cap 20. It will be seen that when the cap 20 is removed, an unimpeded flow path is provided from the bottle neck through the pouring spout and pouring neck; and because of the gently sloping convergence of the annularly shaped spout toward the opening, the issuing stream of liquid will flow smoothly and will have a sharply defined round molded appearance.

In order to secure the pouring spout 14 upon the end of the neck 12, means is provided which forms a permanent connection with the neck and is adapted to maintain the spout rigidly thereon. As herein shown, the neck 12 has an annular channel 22 formed in spaced relation to its outer end so as to provide a head 23. Embracing the head 23 is a skirt member 24 fashioned of suitable sheet metal, which at its lower end is pressed into the groove 22 to form a bead 25, the edge of which lies substantially within the curvilinear plane of the bottle neck so as to prevent the insertion of a tool in an attempt to remove the skirt.

Beyond the end of the bottle neck, the skirt 24 is inwardly offset to provide a shoulder 27 in such relation to the flange 15 as to connect the pouring spout to the bottle neck. To insure a liquid tight joint between the flange 15 and the bottle neck 55 a gasket 28 of liquid-proof and relatively resilient material is provided. This gasket is compressed between the bottle neck and the flange as an incident to the slight longitudinal movement of the skirt and flange relative to the bottle neck 60 resulting during the process of forming the bead 25. Since for practical reasons the spout 14 is preferably formed of relatively thin sheet metal, the pressure of the flange 15 against the gasket 28 may tend to distort the flange. For this reason a metallic disk ring 29 may be fitted to encircle the spout in snugly overlying relation to the flange 15 and directly in engagement with the shoulder 27 to form a reinforcement permitting substantial pressure to be exerted upon the flange. Thus, the pouring spout is rigidly and permanently connected to the bottle neck, and in order to remove the same it will be necessary to destroy the skirt 24.

Bottles in which liquids of known characteristics and quality such as fine beverages are dis-

pensed, are often times refilled with inferior liquid and the imitation disposed of as the genuine product. This fraudulent practice is of damaging consequence to the original producer because the user will not be aware of the deception due to the genuine bottle in which the imitation is sold to him, and will thus unjustly attribute the inferiority of the imitation to the original.

To detect any attempt at such fraudulent practice the present invention contemplates a tamper-proof seal by which a visible disclosure will be had as to whether or not the bottle has been opened. For this purpose a sealing strip 30 of thin, flexible material is secured over the cap 20 so as to be removed or destroyed as an incident to pressure exerted thereagainst when the cap is screwed from the discharge neck 17 in order to open the bottle. As herein shown, the strip 30 may be formed as a narrow band fitting over the crown of the cap 20 and having its ends extending along opposite sides of the cap and lying against the spout 14. A convenient manner of securing the ends of the sealing strip is provided by extending the outer end of the skirt 24 to form an arcuate collar 32 of pleasing contour and having its outer edge turned over to provide a bead 33 adapted for engagement with the shoulder 18. Preferably the arrangement of the collar is such that coincident with assembly of the skirt with the spout the bead 33 will also be brought into proper position. Snug engagement between the bead 33 and the shoulder 18 is assured in the present instance by the provision of a groove 34 in the shoulder; and as may be seen in Fig. 2, the bead serves to anchor the ends of the strip 30 in place by clamping these ends against the shoulder 18. Rigidity of the collar adjacent the bead 33 is insured by the provision of an offset rib 35 which may be seen as breaking the even contour of the collar.

In order to prevent sidewise slipping of the strip 30 relative to the cap 20, the crown of the cap may be provided with a protuberant portion 36 of smaller diameter than the cap, and the sealing strip may be provided with an enlarged portion 37 of similar shape as the crown of the cap and having an aperture 38 through which the portion 36 may protrude. Through this arrangement, the strip will be maintained against lateral slipping and against forceful surreptitious movement to one side. Thus, the cap 20 may be removed only upon removal or destruction of the sealing strip.

A soft ductile material such as sheet aluminum which will break when placed under moderate tension by removal of the cap 20 may be used for the sealing strip. The broken strip will then visually indicate that the bottle has been opened (Figs. 5 and 6). If desired, the sealing strip may be weakened at one or more suitable points so that severance will always occur in a given manner. As seen in Fig. 7, for example, notches 37a may be formed in opposite sides of the enlarged crown portion 37 of the sealing strip. Through this arrangement the strip will be severed medially and similar tabs will remain on opposite sides of the pouring neck (Fig. 8). These tabs offer very little obstruction and are not likely to interfere with a proper discharge of liquid.

In another arrangement the sealing strip may be formed of a material having greater tensile strength so that upon unscrewing the cap the ends of the strip will be withdrawn from their anchored position between the bead 33 and the shoulder 18. To effect this result, the portions 75

of the strip extending between the collar 32 and the body of the pouring spout should be of a length slightly less than those parts of the strip extending from the bead 33 to the crown of the cap, so that when the cap is unscrewed to a position such as shown in dotted outline in Fig. 4 where it can be lifted from the pouring neck, the ends of the strip will be completely released. While the thickness of the sealing strip wherever shown in the drawings is considerably exaggerated for purposes of illustration, it will be understood that in practice an aluminum sealing strip, for example, may be only from .025 to .05 of an inch in thickness. It will thus be clear that the space between the bead 33 and the shoulder will be so minute as to prevent a reinsertion of the ends of the strip and thereby insure that once the seal has been destroyed or removed it cannot be replaced.

20 The present invention contemplates such an arrangement of parts that the closure device may be assembled as a complete, liquid-tight, compact commercial unit which requires no further adjustment after assembly and which may be shipped to the user in readiness to be affixed to a filled bottle by a simple operation. Each part, therefore, has been fashioned with a view to facilitating assembly and union so that the bottle closure may be produced cheaply and in large quantity on a commercial scale. Referring particularly to Figs. 2 and 3, the device may be assembled easily and speedily in a minimum number of steps which may be carried out in substantially the following sequence. The cap 20 may be screwed upon the pouring neck 17 of the spout, following which the disk ring 29 may be positioned about the spout flush against the flange 15, and the sealing strip 30 then fitted about the cap 20 with its ends lying against the shoulder 18 of the spout. Completion of the assembly is effected by placing the skirt member 24 in position about the spout so that the shoulder 27 engages the ring 29 and the bead 33 clamps the ends of the sealing strip in place, and then forming a crimp 39 in the skirt for rigidly connecting the latter to the flange 15. In effect, it will be observed, the adjoining edges of the flange 15 and the ring 29 are gripped permanently within a laterally protruding channel 40 in the skirt. Following assembly, all that remains to permanently affix the closure unit to the bottle is to place the gasket 28 upon the end of the bottle neck, position the unit by slipping the skirt over the head 23 of the neck, and spinning or otherwise pressing the bead 25 into the channel 22.

60 After the closure unit has been affixed to the bottle neck, the cap 20 may be tightened slightly if desired, but it will be impossible to remove the cap even partially without appreciably visibly affecting the sealing strip. Where the sealing strip is of low tensile strength or has been designedly weakened for the purpose, the force exerted thereon as an incident to unscrewing the cap will cause the same to break; and where the strip is of greater tensile strength, the ends thereof will be pulled from their clamped position. Preferably the material of the strip is such that it cannot be repaired, and replacement is not possible because the clearance between the bead 33 and the shoulder 18 is of such minute character as to prevent return of the strip once it has been withdrawn. The rigidity imparted by the bead 33 and the offset 35 prevents stretching the 70 edge of the collar with an instrument to effect

a sufficient opening to reinsert the end of the sealing strip. Moreover, due to its pliable or ductile character the sealing strip will present no sharp or jagged edges which might cause injury to a person's hand either when turning the cap 20 or after the sealing strip has been broken.

75 As will be apparent, the sealing strip 30 coacts with that part of the device which is of substantially the smallest diameter and which is so disposed that in handling or shipment of the assembled unit, either before or after the device has been assembled with a container, the parts of the device having greatest diameter will serve as buffers to guard the sealing strip from damage that might result from contact with objects in relative motion. After the sealing strip has been broken, the major portions of the severed parts thereof projecting from the joint between the shoulder 18 and the cooperating bead 33 on the retaining collar 32 may be torn away; but the relationship of the elements of the device is such that only with great difficulty and never with the fingers of a hand alone can sufficient grip be had on the severed parts of the strip in order to remove every exposed portion thereof. As a result, even after the principal portions of the severed parts of the strip have been torn away, small tabs will remain in evidence adjacent the base of the pouring neck 17. As seen in Fig. 6, when the sealing strip is ruptured immediately adjacent the shoulder and collar joint in the opening movement of the closure cap, a short, substantially permanent tab is provided at once. Thus, the sealing strip after it has been ruptured leaves in evidence on the device visible proof indicating that the container is no longer in its original state.

80 Because of its tapered annular construction, the pouring spout facilitates a restricted discharge of liquid from the bottle. Upon referring to Fig. 5, which represents a condition existing when the bottle is still substantially full of liquid, it will be seen that a substantial passage 43 is provided for entry of air to the interior of the bottle for replacing liquid discharged therefrom. 85 This passage is of substantial proportions and by permitting a free inflow of air eliminates a tendency of the liquid to surge or gush forth from the pouring neck. Thus, the quantity of liquid discharged may be controlled with considerable 90 certainty. Moreover, the gradually tapered form of the annular spout has the effect of molding a smooth and uniform stream of flowing liquid which will facilitate pouring the liquid into a receptacle 44. The molded characteristics of the 95 stream will be evident in any pouring position of the bottle, Fig. 6 illustrating this effect when pouring liquid from a relatively exhausted bottle.

I claim as my invention:

1. The combination with a bottle having a protruding neck, of a closure device including a sheet metal pouring spout having a substantially frusto-conical body with a base of about the same interior diameter as that of said bottle neck so as to provide a substantially unrestricted flow path and air passage therethrough, a lateral flange around said base adapted to overlie the end of said bottle neck, a pouring neck of substantially smaller diameter than said base on the outer end of said spout and having cap engaging means thereon, a cap secured to said pouring neck for closing the same against escape of liquid and having a crown protuberance, an offset shoulder on said spout between the body and said pouring neck, a member encircling said 75

- body including an inwardly extending outer edge with a turned-over bead engaging said shoulder and being secured near its outer end to said bottle neck so as to connect said spout permanently to said neck, a gasket between said flange and bottle neck, a rigid disk ring fitting around said body to overlie and reinforce said flange, said member being fashioned intermediate its edges to engage said ring and flange for drawing the same toward said bottle neck to compress said gasket and provide a liquid tight joint, and a thin sealing strip having an apertured intermediate portion fitting over said cap with said protuberance fitting therethrough and having a pair of oppositely extending narrow legs clamped between said shoulder and said bead so that said strip must be removed or destroyed in order to remove said cap.
2. The combination with a bottle having a protruding neck, of a closure device including a sheet metal pouring spout having a substantially frusto-conical body with a base of about the same interior diameter as that of said bottle neck so as to provide a substantially unrestricted flow path and air passage therethrough, a pouring neck of substantially smaller diameter than said base on the outer end of said spout and having cap engaging means thereon, a cap secured to said pouring neck for closing the same against escape of liquid and having a crown protuberance, an offset gently arcuate shoulder on said spout between the body and said pouring neck, a member encircling said body including an inwardly extending outer edge with a turned-over bead engaging said shoulder and being secured near its other end to said bottle neck so as to connect said spout permanently to said neck, and a thin sealing strip having an apertured intermediate portion fitting over said cap with said protuberance fitting therethrough and having a pair of oppositely extending narrow legs clamped between said shoulder and said bead so that said strip must be removed or destroyed in order to remove said cap.
3. A bottle closure device including in combination, an annular pouring spout having a pouring neck of substantially less diameter than the body of the spout, a shoulder formed intermediate said pouring neck and said body, a cap closing the opening to said pouring neck and having an axial protuberance, a sealing strip fitting over said closure and having its opposite ends in engagement with the pouring spout adjacent said shoulder, said strip having an aperture through which said protuberance is adapted to fit so as to prevent slipping of the strip relative to the cap, and means for clamping said ends against said shoulder so as to prevent removal of said cap without visibly affecting said sealing strip.
4. The combination in a bottle closure, of an annular pouring spout member having a lateral base flange adapted to overlie the edge of a bottle neck, an encircling member having means engaging said flange and adapted to connect the spout to the bottle neck, and a flat annular reinforcing element lying flush against said flange in order to prevent distortion thereof when pressure is exerted upon said flange incident to affixing the spout to the bottle neck.
5. The combination in a bottle closure, of an annular pouring spout member having a bendable lateral base flange adapted to overlie the edge of a bottle neck, a resilient gasket between the flange and bottle neck, an encircling member

having means engaging said flange and adapted to connect the spout to the bottle neck, and a flat annular reinforcing element lying flush against said flange between said flange and said means in order to prevent distortion of the flange when pressure is exerted thereon incident to affixing the spout to the bottle neck.

6. In a unitary device of the character described, the combination of an annular sheet metal pouring spout member having a lateral base flange, an encircling member having means lying on opposite sides of the periphery of said flange for connecting the parts permanently and inseparably together, and a flat annular reinforcing element clamped by said means into flush engagement with one side of said flange and serving to prevent distortion thereof during assembly of the parts.

7. In a container closing device, the combination of a sheet metal generally annular member dimensioned to fit about the mouth and neck of a container and to be permanently secured thereto, a detachable closure for the outer end of said member, sealing means connected with said member to pass across said closure, and interengaging means on said sealing means and closure for preventing lateral movement of said sealing means relative to said closure.

8. In a device of the character described for assuring the genuine character of the contents of a container, a closure member for the pouring outlet from the container having exterior surface for engagement by the fingers of a hand for removal from the outlet, said member having a crown protuberance, and a fragile strip extending across said member in such relation as to leave said exterior surface exposed and having its opposite ends fixedly secured against movement relative to the container so that removal movement of said member will cause the strip to be torn, said strip including means in the portion overlying the crown of said member co-active with said crown protuberance to maintain the strip against transverse displacement from said crown.

9. Tamper resisting means adapted for assuring the bona fide nature of the contents of a container having a screw cap closure comprising a thin, readily destructible member having an enlargement dimensioned to cover at least a part of the top of the closure and to encircle a portion thereof to hold the member against accidental transverse displacement therefrom but enabling the closure to be manipulated for rotary movement relative to the member, and elongated portions extending from spaced outer marginal points on said enlargement to be clamped permanently and inseparably to the container adjacent to the base of said closure, said elongated portions being tearable between the ends thereof in the opening movement of said closure so as to leave irreparable evidence of such movement.

10. In combination with a container having a discharge spout, a screw cap closing said spout, an axial annular exterior protuberance upon the crown of said cap, a thin sealing member having an intermediate part fashioned to receive said protuberance and end portions extending along and beyond opposite side areas of said cap and exposing the sides of said cap between said end portions to permit the cap to be readily grasped and rotated, and means for securing said end portions irreplaceably in position beyond said side areas taut enough to prevent lateral displacement of said intermediate part from said

protuberance but permitting rotation of said cap to tighten the latter and assuring that said end portions will be permanently disrupted by unscrewing said cap.

- 5 11. In combination in a bottle closure device, a generally tubular member having a discharge passage therethrough and including an annular lateral flange adapted to overlie the edge of a bottle neck, and a coaxial tubular element for securing said member to the bottle neck encircling said member and extending substantially beyond the opposite sides of said flange, said securing element including a skirt portion adapted to be permanently affixed to the bottle neck and a
- 10 15 converging portion beyond said skirt portion, said portions having a laterally projecting channel therebetween within which said flange is fixedly engaged and which defines a fixed position for said flange to unite said members permanently

together so that the device can be handled as an inseparable unit before application thereof to the bottle, a closure for said discharge passage, and means for preventing tampering.

12. A tamper-proof closure device comprising, 5 in combination, a tubular member having a lateral annular flange, a cap threaded on said member, a tamper-proof sealing strip extending across said cap and having its ends extending longitudinally along said cap and beyond the rim 10 thereof, and a member for securing the device to a bottle neck including a portion projecting inwardly to engage and clamp said strip against said member as well as a skirt to engage the bottle neck and a channel between said portion and 15 said skirt in which said flange is secured permanently to maintain a fixed clamping relationship of said portion upon said strip ends.

MERRILL M. KISTNER.
